WILLIAM BURDITT AND GEORGE H. BURDITT, OF BOSTON, MASSACHUSETTS.

Letters Patent No. 85,428, dated December 29, 1868.

IMPROVEMENT IN DRIVE-WELLS.

The Schedule referred to in these Letters Patent and making part of the same.

To all whom it may concern:

Be it known that we, WILLIAM BURDITT and GEORGE H. BURDITT, of Boston, in the county of Suffolk, and State of Massachusetts, have invented a new and useful Improvement in Driven Pumps; and we do hereby declare that the following is a full, clear, and exact description of the same, reference being had to the annexed drawings, making part of this specification, in which—

Figure 1 is an elevation;

Figure 2, a vertical longitudinal section of the filter;

Figure 3, a vertical section of the tube, and plug used in sinking the tube;

Figure 4, a similar section, showing another arrangement for the filter; and

Figure 5 is a perspective view of the screen used for confining the gravel used as a filter.

The same letters indicate the same parts in all the figures.

Our improvements consist in the use of a jointed plug, which, filling the lower section of the pump-tube while being driven, serves to exclude the earth, &c., from the latter, and which may be drawn out when the pump has been driven, and also in filling the lower section with gravel or other suitable material for a filter for the water, which is kept in place by means of a peculiarly-shaped screw, forced down through the tube, and resting thereon.

In the annexed drawings—

A is the lower section of the pump-tube, being a metallic pipe of strength sufficient to resist the blows necessary to force it into the earth.

It is terminated by a sharp steel point, B.

The section A is perforated by small holes.

To exclude the earth from these holes while the tube is being driven, a jointed plug, C, is inserted in the lower section. This plug we form of a series of pieces, concave on their lower ends, and convex on their upper ends, so that the pieces, while forming a compact plug when resting on one another, may have the flexibility required to enable them to pass any bends that may be formed in the pipe while being driven.

A chain, D, is attached to the plug, for the purpose of drawing it up when the well is completed. The chain must be lengthened by attaching new pieces, as the successive sections are attached to the tube as it is forced into the ground.

When the tube is driven to the proper depth, the

lower section thereof should be filled with gravel or other material suitable for filtering the water; and, in order to keep the gravel or other material in place, and prevent it being drawn up with the water, to the injury of the valves, we cover it with a screen, F, which consists of a thin metallic disk, bent into a concavo-convex form, and having radial slits extending from the periphery. The inner portion is perforated with small holes, sufficient to permit the required quantity of water to flow through the screen F.

The form of the screen permits it to be easily forced down to the gravel or other material. The convex face being down, it passes freely downwards, the portions between the slits yielding readily; but when the screen is down, these arms, pressing against the sides, will resist any pressure from below, upwards.

We have shown, in fig. 4, a modification in the construction of the filter. Instead of filling the lower section with the filtering-material, we introduce therein a wire screen, G, the meshes of which will exclude particles of sand fine enough to pass through the holes in the section.

Within this screen is a tube, H, perforated with fine holes. This tube is the lower section of the pump.

The intermediate space between the screen G and tube H is filled with filtering-material. A coarser material may be introduced between the section A and the screw G.

In fig. 5, we have shown a screen adapted to this form of filter. The central tube will embrace the tube H, or it may be used with only a round hole fitting that tube.

What we claim as our invention, and desire to secure by Letters Patent, is—

In combination with a pump-tube, of the class that is driven into the ground without first digging or boring a hole, a perforated screen, containing some filtering-material, and an elastic concavo-convex screen, F, arranged to operate substantially as and for the purpose set forth.

In testimony whereof, we have signed our names to this specification, in the presence of two subscribing witnesses.

WILLIAM BURDITT.
GEO. H. BURDITT.
